UNITED STATES PATENT OFFICE
CERTIFICATE OF CORRECTION

PATENT NO. : D-274,776

DATED : 7/24/84

INVENTOR(S) : Patrick J. Molloy and R. Stanley Lambert

It is certified that error appears in the above-identified patent and that said Letters Patent are hereby corrected as shown below:

On the first page of the patent the first sentence beneath the sub-heading "DESCRIPTION" should read as follows:

"FIG. 1 is a top plan view of a scoop embodying our new design;"

The final sentence on the first page of the patent under the sub-heading "DESCRIPTION" should read as follows:

"The side not shown is a mirror image of the side shown in FIG. 2."

Signed and Sealed this

Twenty-ninth Day of January 1985

[SEAL]

Attest:

DONALD J. QUIGG

Attesting Officer

Acting Commissioner of Patents and Trademarks
